STANDARD ENGINEERING COMPANY, OF ST. LOUIS, MISSOURI, A CORPORATION.

COMBUSTION SYSTEM.

Application filed February 8, 1919. Serial No. 275,788.

To all whom it may concern:

Be it known that we, LEWIS L. SCOTT and ALLEN C. STALEY, citizens of the United States, residing in the city of St. Louis 5 and State of Missouri, have invented new and useful Improvements in Combustion Systems, of which the following is a specification.

This invention relates to certain new and 10 useful improvements in combustion systems, and particularly of the type disclosed in application of Lewis L. Scott, Serial No. 241,590, filed June 24, 1918.

One of the objects of the invention is to 15 provide a fuel feed regulating device, whereby to prevent the kerosene, or other oil, fed to the spray nozzle, from dripping or running through the nozzle on starting the system in operation and before the pressure 20 has built up sufficiently to cause the fuel oil to spray.

Another object of the invention is to initially retard the production of ignition 25 relative to the supply of air, and preferably by providing means for retarding the spraying of the fuel oil until the air supplied to complete combustion of the fuel has had time to enter the combustion chamber and drive out spent gases remaining 30 from a prior operation, so that the ignition of the oil may occur immediately upon the spray starting.

A final object of the invention is to provide automatically operating means, shown, 35 in the present embodiment of the invention, in the form of a check valve located in the air duct through which air passes to the combustion chamber, to prevent heat and products of combustion from passing 40 back into the fan casing and thence to the outer air when the operation of the fan is stopped.

In the drawing, the figure is a view partly 45 in section and partly in elevation of so much of the Scott system as is necessary to illustrate the location and operation of our improvement.

Referring to the drawing, the numeral 1 indicates a steam generator, of the type 50 shown in the application referred to, which is inclosed in a casing 2 having an air chamber 3 provided on its top and communicating with an air duct 4. In the top 55 of the air chamber is located a primary combustion chamber 5 which is surrounded

by a spout 6 leading from the air chamber. The numeral 7 indicates the spray nozzle for spraying fuel into the chamber 5, and the numeral 8 the spark plug for igniting the sprayed fuel. The spray nozzle 7 is 60 connected to and communicates with a valve casing 9 in which is seated a valve 10 the stem 11 of which is guided in a housing 12 and works against a spring 13 mounted in said housing. The pressure of 65 the spring 13 is adjusted to hold the valve 10 to its seat under a given pressure, which, in the system referred to, would be about 10 lbs. The numeral 14 indicates the fuel oil supply pipe which communicates with 70 the casing 9 below the valve 10. The valve 10 governs a port affording communication between the pipe 14 and spray nozzle 7, and by its spring 13 controls the pressure 75 at which the fuel oil shall pass to the spray nozzle.

Located at any suitable point in the length of the pipe 14 is a pressure chamber 15, which communicates with said pipe. The purpose of this chamber will be presently 80 described. The numeral 16 indicates the fuel oil tank which communicates by a pipe 17 with a pump 18 driven from a motor 19, and a pipe 20 leads from the pump to the pipe 14, the latter communicating 85 with a by-pass 21 from which a pipe 22 leads to the suction side of the pump. The by-pass is controlled by a solenoid valve 23. The numeral 24 indicates the water tank from which a pipe 25 leads to a pump 90 26, also operated by the motor 19. A pipe 27 leads from the pump 26 to the steam generator 1. The electrical and other connections are indicated diagrammatically, but not described, as they form, as such, no part 95 of the present invention.

Referring now to the pressure chamber 15, it will be clear that with the pump 18 in operation forcing the fuel oil through the pipe 14, the said chamber must first be 100 supplied with the oil and the pressure thereof against the air trapped in said chamber built up before the pressure of the oil can effect a lifting movement of the valve 10. This will necessarily delay the period when 105 the oil will be sprayed from the nozzle 7, and during this interval the air passing into the combustion chamber through the duct 4 will carry away the spent gases that may have remained from a prior operation, 110

insuring, when the oil is finally sprayed, an atmosphere of pure air for the initial and complete combustion of the fuel. By adjusting the size of the chamber 15, the retardation of the spray of the oil may be varied in degree as may be found desirable.

When the pressure of the fuel oil in pipe 14 and chamber 15 has been built up to, say, 10 lbs., the valve 10 will be lifted 10 from its seat and the oil under pressure pass to the spray nozzle 7, thus insuring that any oil escaping from said nozzle will be in the form of a spray. As soon as the pump 18 stops, and the pressure in the pipe 15 falls below 10 lbs., the valve 10 will be forced to its seat by the spring 13, thus preventing the passage of further oil to the spray nozzle, and its escape therefrom in drops, or a small stream, in which condition 20 it is practically non-ignitable by the electric spark.

The final feature of our invention resides in the provision of suitable means to prevent back-flow of products of combustion 25 into the fan casing. This casing is indicated at 28 and is connected to the air duct 4. To illustrate one way of accomplishing the above object, we show located, at any suitable point in the air duct, a flap-valve 30 29 hinged at one side to the side of the air duct, as shown at 30 and resting upon a seat 31. This valve is quite light and readily opens outwardly, or, in the case shown, upwardly, under air pressure, and will remain 35 in such position as long as air is being forced through the duct 4. When the fan stops, the air pressure ceases and the valve 29 at once drops to its seat 31, closing the air duct 4 against backflow of hot gases, 40 and products of combustion, from the combustion chamber. In this way we prevent the waste of heat that would otherwise occur when the fan was not operating.

What we claim is:—

45 1. In a combustion system, an oil projecting device, means for supplying oil thereto under pressure and thereby spraying it, means for igniting the sprayed oil, means for continuously supplying air to the ignited spray to promote combustion of the oil, and automatic means for initially retarding the production of ignition relative to the supply of air.

55 2. In a combustion system, an oil projecting device, means for supplying oil thereto under pressure and thereby spraying it, means for igniting the sprayed oil, means for continuously supplying air to the ignited spray to promote combustion of the oil, and 60 means for initially retarding the projection of the oil relative to the supply of the air.

65 3. In a combustion system, a spray nozzle, means for feeding fuel oil thereto under pressure and thereby spraying it, means for

igniting the sprayed oil, means for continuously supplying air to the ignited spray to promote combustion of the oil, and means for initially retarding the spray of the oil relative to the supply of the air.

4. In a combustion system, in combination with a spray nozzle, means for supplying fuel oil thereto under pressure and thereby spraying it, means for igniting the sprayed oil, means for continuously supplying air 70 to the ignited spray to promote combustion of the oil, means common to said fuel and air supply for causing the same to be propelled independently and simultaneously, and automatic means for initially retarding the 75 advent of the oil to the spray nozzle relative to the supply of air to the sprayed oil.

5. In a combustion system, a device for spraying fuel oil by pressure for burning, a pipe for supplying the oil to said device, 85 means for forcing oil under pressure through said pipe to the spraying device, and means interposed in the length of said pipe for creating a spraying pressure on the oil before its advent into said device.

90 6. In a combustion system, a device for spraying fuel oil by pressure for burning, a pipe for supplying the oil to said device, means for forcing oil under pressure through said pipe to the spraying device, 95 means interposed in the length of said pipe for creating a spraying pressure on the oil before its advent into said device, and a pressure chamber communicating with said pipe between said pressure-creating means 100 and said oil-forcing means for increasing the time of establishing the spraying pressure on the oil.

7. In a combustion system comprising a device for spraying oil for burning, means for initially admitting oil to said device under a spraying pressure, means for supplying air to the zone of the sprayed oil, actuating means for simultaneously and independently propelling the air and oil, and 110 means operating automatically to retard the creation of a spraying pressure of the oil until the air has been supplied to the zone of the sprayed oil.

8. In a combustion system, in combination with a spray nozzle, a pipe for supplying oil to said nozzle to be sprayed for burning, a valve governing the supply of said oil, means operating said valve to create a given pressure on the oil before its admission to the nozzle, a hollow chamber communicating with said pipe for retarding the creation of such pressure, means for supplying air to the zone of the sprayed fuel, and means common to the oil and air supply 120 means for simultaneously propelling said air and oil.

9. In a combustion system, in combination with an inclosed combustion chamber, an air duct communicating therewith, means for 130

propelling air through said duct, and means for preventing a back-flow of heat and products of combustion from said combustion chamber through said air duct to the outer air.

10. In a combustion system, in combination with an inclosed combustion chamber, an air duct communicating therewith through its top, means for propelling air through said duct, and means for preventing a back-flow of products from said combustion chamber through said air duct.

11. In a combustion system, in combination with an inclosed combustion chamber, an air duct communicating therewith through its top, means for propelling air through said duct, and a valve in said duct adapted to open under pressure of the propelled air and to close in the absence of said pressure to prevent back-flow from the combustion chamber through said air duct.

12. A steam generating system comprising a combustion chamber, a boiler inclosed therein, a fuel burning system of the type adapted to be turned on and off according to

generator conditions and including a burner located in said combustion chamber, and means for preventing the back flow of heat from the combustion chamber when the fuel burning system is shut off.

30

13. In a combustion system, an oil spraying device, means for supplying oil thereto, means for igniting the sprayed oil, means for furnishing air to complete combustion of the oil, means for retarding the supply of one of the combustion promoting elements.

14. In a combustion system, an oil projecting device, means for supplying oil thereto under pressure and thereby spraying it, means for igniting the sprayed oil, means for continuously supplying air to promote combustion of the oil, and means for producing a relative retardation between the projection of the oil and the supply of the air.

In testimony whereof, we have hereunto set our hands.

LEWIS L. SCOTT.
ALLEN C. STALEY.
